BOX-SPRING ASSEMBLY
 Robert Goodman, 5325 Westminster Ave.,
 Philadelphia 31, Pa.
 Filed Feb. 5, 1963, Ser. No. 255,523
 4 Claims. (Cl. 5—230)

This invention relates to box spring assemblies for beds, sofas and the like, and particularly to assemblies of this type where the spring provides a constant flexible support for a load regardless of the weight or position of the load thereon. This application is a continuation-in-part of co-pending application Serial No. 177,784, filed March 6, 1962, now Patent No. 3,119,126.

As disclosed in the aforementioned co-pending application, heretofore the box springs included a series of vertical coil springs situated between the upper and lower deck and flexibly supporting the upper deck consisting of a cross-wire network. These supporting coil springs tended to become distorted in certain areas due to constant positioning of the load in such areas, so that the desired resilience and flexible support was largely lost in such areas. In addition, these coil springs being of constant strength and flexibility, would not give the same support to varying loads.

The aforesaid disadvantages of the prior art were overcome by the construction disclosed in said co-pending application whereby a series of pivotal arms are substituted for the vertical coil springs, these pivotal arms being arranged in pairs of oppositely-swinging arms. When a load is placed on any portion of the upper deck, and regardless of its weight, the force of the weight is transmitted equally to the oppositely-pivoted arms which then swing down equally an amount sufficient to counterbalance the weight of the load.

In order to eliminate any tendency for the upper deck to sag in the middle because of the unequal distribution of weight in a person's body as between the heavier torso and the lighter head and legs, it was proposed in said co-pending application to provide bowed spring strips extending transversely of the assembly between each pair of oppositely-pivoted supporting arms, these bowed springs being connected at their ends to the arms and bearing at their centers on the underside of the upper deck. Although these bowed springs did, to an appreciable extent, prevent sagging, they did so only in the transverse areas in which they themselves were positioned and there was still considerable sagging between them. On the other hand, if a sufficient number of such transverse springs were used so that the spaces between them were too small to permit sagging, there would be so many of these springs that they would tend to rigidify the assembly and so defeat its primary purpose of resiliency. In addition, since these springs were connected to the pivoted arms, the tension thereon would constantly alternate in conjunction with the movement of the arms so that spring fatigue would occur in a relatively short time.

It is one object of the present invention to retain all the advantages inherent in the construction disclosed in said co-pending application while eliminating the disadvantages thereof by providing spring support units which fully prevent sagging of all parts of the upper deck and which are not subject to undue stresses and strains with consequent spring fatigue.

Another object of the present invention is to provide a box spring assembly of the aforesaid type which is sturdy, relatively simple in construction and inexpensive to manufacture.

Other objects and many of the attendant advantages of the present invention will be readily appreciated as the same becomes better understood by reference to the fol-

2

lowing detailed description when considered in connection with the accompanying drawings wherein:

FIG. 1 is an exploded perspective view of a box spring assembly embodying the present invention, the fabric cover portion being similar to that disclosed in said co-pending application but being omitted here for purpose of clarity.

FIG. 2 is a cross-sectional view of the assembled device of FIG. 1, with the cover again omitted for clarity.

FIG. 3 is a fragmentary, sectional view of an edge portion of the assembly of FIGS. 1 and 2, with the cover in position.

Referring in greater detail to the drawings wherein similar reference characters refer to similar parts, there is shown a box spring assembly, generally designated 10, comprising an upper deck 12 and a lower deck 14. The upper deck 12, similarly to that disclosed in said co-pending application, comprises a generally rectangular, tubular frame 16 having rounded corners 18 and constructed of generally flexible material such as spring metal or the like. Stretched between the ends and sides of the frame 16 is a cross-wire or lattice network 18 wherein the cross-wires are attached to their respective side or end sections of the frame 16 by springs 20 connected therebetween.

The lower deck 14 comprises a generally rectangular frame 22 having rounded corners 24 and preferably constructed of separate side and end strips connected to each other at these rounded corners by any desirable means such as screws, nuts and bolts, adhesive, etc. The frame 20 is shown constructed of wood, but metal or any other desirable material may be used and is sometimes even preferable.

Extending across the frame 22 are a plurality of spaced, parallel cross-bars 26, preferably of angle-iron, which are secured at their ends to the respective side sections of the frame 22 by any means desired. Pivoted connected to the vertical portion of each cross-bar 26, as at 28, are a pair of arms 30, the arms of each pair being laterally spaced from each other and extending diagonally upward and outward in opposite directions from each other. At its upper end, each arm 30 is provided with an offset portion 32 which engages within a corresponding slot in the corresponding side of the frame 16. Each arm 30 is also provided at its lower end with an offset stop member 34 adapted to abut the horizontal portion of the corresponding cross-bar to limit pivotal movement of the respective arm.

An additional pair of pivotal arms 36 are provided, one at each end of the assembly, each arm 36 being pivoted at 38 to a bracket 40 extending perpendicularly from the corresponding end cross-bar 26. Each arm 36 is provided with an offset upper end portion 42 connected to the ends of the frame 16 in a manner similar to the attachment of the portions 32 of the arms 30 to their respective frame sides.

The arms 30 act in the manner described in said co-pending application wherein, with no load on the upper deck, the springs 20 at the sides of the upper deck exert a force in equilibrium with the force of gravity acting to pivot the arms 30 downwardly. Similarly, the arms 36 at the ends of the assembly are in equilibrium with the springs 20 at the ends of the upper deck. When a load is placed on any part of the upper deck, the force is transmitted to all the arms 30 and 36 equally whereby these arms spread to uniformly compensate for the load.

Although the arms 30 and 36 compensate for the load both laterally and longitudinally, the problem of sag of the cross-wire network of the upper deck, as described in the said co-pending application, would still exist. This problem is eliminated by a pair of spring rods 44 which are slightly arched throughout their major length but are

provided with downwardly offset end portions connected by any means desired, such as riveting, welding, nuts and bolts, screws or the like, to corresponding end cross-bars 26. In the form shown, the spring rods 44 are positioned between the opposite arms 30 of each pair and the ends of the spring rods are connected by rivets 46 to the respective cross-bars. The central portions of the spring rods 44 are connected to the cross-wire network of the upper deck by tie wires 48 (as shown in FIG. 2).

By the above construction, the spring rods 44 provide a flexible support for the upper deck throughout the length thereof while, at the same time, a minimum area of contact is established so that there is no resulting over-support and consequent undesirable rigidity. These spring rods 44, being independent of the pivotal arms 30 and 36, are also free from undue stress which might result from constant flexing and unflexing in conjunction with the pivotal movement of these arms.

An enveloping cover 50, such as described in the aforementioned parent application Serial No. 177,784, may be provided. This cover, as explained in the said parent application, is connected to the inner framework only at the bottom of the lower deck 14 so that, as the upper deck 12 shifts position, the cover 50 also shifts its position.

Obviously many modifications and variations of the present invention are possible in the light of the above teachings. It is, therefore, to be understood that within the scope of the appended claims, the invention may be practiced otherwise than as specifically described.

The invention claimed is:

1. A box spring assembly comprising an upper generally rectangular deck, a lower generally rectangular deck and supporting means between the upper and lower decks, said upper deck comprising a frame having sufficient flexibility to permit expansion of the frame under the force of a load but being sufficiently rigid to be moved bodily by said force, said frame having a spring-tensioned cross-wire network extending thereacross, and said supporting means comprising at least one pair of arms individually pivoted to said lower deck and being laterally spaced from each other, said arms extending upward and outward from their respective pivot points in opposite directions relative to each other and being fixed to opposite portions of the frame of said upper deck, and a plurality of laterally-spaced spring rods extending longitudinally of said assembly, said spring rods being connected at their ends to said lower deck and having upwardly arched central portions bearing upon said upper deck, said supporting means consisting of said arms and said spring rods, and said upper deck being supported solely by said supporting means.

2. The assembly of claim 1 wherein there are at least two pairs of arms, the arms of one pair of arms being spaced from each other transversely of the longitudinal extent of said assembly and the arms of another pair of arms being spaced from each other longitudinally of said assembly.

3. The assembly of claim 1 wherein a flexible cover envelops said upper deck and said supporting means, said cover being attached to said lower deck and being distortable into varying contours responsive to the varying positions of said upper deck.

4. A box spring assembly comprising an upper deck, a lower deck and supporting means between the upper and lower decks, said upper deck comprising a frame having sufficient flexibility to permit expansion of the frame under the force of a load but being sufficiently rigid to be moved bodily by said force, said frame having a spring-tensioned cross-wire network extending thereacross, said lower deck comprising a rigid frame having a plurality of spaced, parallel cross-bars extending thereacross, each 10 of said cross-bars being an angle-bar having a vertical web and a horizontal web, a pair of arms individually pivoted to the vertical web of each cross-bar, the arms of each pair being spaced from each other at their pivot points and extending upwardly and outwardly from their pivot points in opposite angular directions, the arms of each pair being rigidly connected to a corresponding portion of the frame of the upper deck, each arm having an extension adjacent its pivot point and extending oppositely from the arm itself, said extension being arranged to abut the horizontal webs of their corresponding cross-bars at predetermined positions of their respective arms, an additional pair of arms, one of said additional arms being pivotally connected to one endmost cross-bar and the other of said additional arms being pivotally connected to the 15 other endmost cross-bar, said additional arms extending angularly upward and outward in opposite directions and in a plane transverse to the longitudinal extent of the angle bars, said additional arms being rigidly connected to corresponding portions of said frame of the upper deck, 20 and a pair of laterally spaced, parallel, upwardly-bowed spring rods connected at their opposite ends to said lower deck and extending transversely of said angle bars, said spring rods bearing against the cross-wire network of said upper deck, said supporting means consisting of said arms, 25 said additional arms and said spring rods, and said upper deck being supported solely by said supporting means.
